UNITED STATES PATENT OFFICE.

JULIUS HEINZ, OF SUTTON, NEBRASKA.

RAILWAY WEED CUTTER.

Application filed January 5, 1924. Serial No. 684,537.

To all whom it may concern:

Be it known that JULIUS HEINZ, a citizen of the United States, residing at Sutton, in the county of Clay and State of Nebraska, has invented certain new and useful Improvements in Railway Weed Cutters, of which the following is a specification.

This invention is in the way of a railway weed cutter or mower, and the object is to provide a relatively simple and practical implement of this kind, adapted for mounting upon a truck, hand car or the like, so that it can be moved along a railroad and operated for cutting the weeds and grass at either side of the track.

In the drawing—

Figure 1 is a rear elevation of the machine as mounted upon the truck for operation on a railroad;

Figure 2 is a plan view;

Figure 3 is a side elevation;

Figure 4 is a detail of the telescoping drive bar;

Figure 5 is a detail of the sickle elevation lever;

Figure 6 is a detail showing the mounting of the mower track upon the railway truck.

In combination with the railway truck 1, moving on the railroad track 10, the invention includes a mower track 2 mounted transversely on the truck 1, the said track 2 being made up of spaced channel rails 3 secured in parallel elevated position by clamps 4 which are in turn bolted to the lower cross ties 5 secured to the truck 1. The channels of the rails 3 are turned inwardly, and slidably engage the horizontal flanges 6 of the angle bars 7. The vertical flanges 8 of the angle bars 7 are bolted to the outer vertical sides of the stringers 9. The stringers 9 are held apart and the horizontal flanges 6 of the angle bars 7 are held in sliding engagement with the channels of the rails 3 by means of spacing beams 11 laid across and secured to the stringers at each end of the structure, and a foot-board 12 is mounted upon the ties 5, thus completing a frame 13, which is slidably mounted upon the truck and adapted to support the other elements of the invention as well as the operator. An engine 14 is mounted at one end of this sliding frame 13, the same having a pulley wheel 15. Upon the opposite end of this frame is erected a vertical sickle supporting frame 16, comprising side beams 17 secured to the ends of the stringers

9, cross braces 18 fastened to the beams 17, and back braces 19. A main drive shaft 20 is journaled at 21 across the top of the sickle frame 16, and carries medially a bevel gear 22 and at its rear end a pulley wheel 23 aligned with the pulley 15 of the engine. The sickle frame 16 depends at one side of the truck 1, as shown, and from this lower end is pivotally supported the usual mower head 24, by means of a V-shaped brace 25, the apex of the brace being pivotally connected at 26 to the head 24, and the ends thereof being pivoted for vertical movement at the points 27 to the frame 16. A telescoping drive shaft 28, made up of a squared bar 29, telescopically mounted in a squared sleeve 30, is connected by means of a universal joint 31 to a jack shaft 57 journaled at 58 to the lower brace 18, and the shaft 57 carries at its upper end a bevel gear 32 in mesh with the gear 22; while the lower end is journaled through the housing 33 and carries a bevel gear 34 in mesh with a similar gear 35 on the sickle drive shaft 36 which drives the pitman rod 37 attached to the sickle blade 38. The drive shaft 36 is journaled through the housing 33 at the points 56. The sickle blade is slidably mounted in the sickle bar 39, which is pivoted to the sickle head 24, all in usual form. A hoisting chain 40 is attached at 41 to the V-brace 25, extended over a pulley 42 secured to the brace 18 at the point 43, and fastened to a lever 44 at the point 45, whereby means are afforded for hoisting the entire working end of the apparatus, including the V-brace 25, clear of any obstruction, or while the apparatus is being moved from place to place.

Finally, a sickle elevating leverage system is provided, the same including the vertical bar 46 journaled at 47 to the forward side of the frontal beam 17, and being formed with a crank arm 48 at the top end, a lever arm 49 at the lower end, and an eye 50 at the extremity of the latter. A link 51 is then pivoted at 52 to a vertical lug 53 on top of the sickle bar 39, and the opposite end is provided with an eye 54 which is linked through the eye 50 of the arm 49. By turning the crank arm 48, the sickle bar 39 is elevated while the V-brace 25 remains stationary. Thus the sickle and bar may be raised independently of the V-brace 25, for passing over some temporary obstruction. This mower is operated by a belt 55

connecting the pulleys 15 and 23. The truck 1 is pushed along the track at the same time that the mowing machinery is in operation, thus cutting the weeds along the right of way. By means of the sliding frame 13, which may be thrust out laterally or drawn in, as desired, means are afforded for widening the extent of the cut or swath. By means of the pivotal mounting of the V-brace 25 and sickle bar 39, these elements may be readily lowered at a descending angle, in order to cut the grass along the sloping sides of a road bed.

While I have herein described a certain specific manner and method of constructing and assembling the elements of my invention, it is understood that I may vary from the same in minor details, not departing from the spirit of my invention, so as best 20 to construct a practical device for the purpose intended, as defined in the appended claim.

I claim:

In combination with a railway truck 25 means for adjustably and operatively mounting the cutting elements of a grass

mower upon said railway truck, said means comprising a frame on the truck adapted for lateral sliding movement thereupon; a sickle supporting frame attached at an end of the sliding frame and depending at the side of the truck; a brace connecting the sickle head to the lower end of the sickle frame for vertical pivotal movement; means for elevating the sickle bar, said means comprising a vertical bar pivoted to the sickle frame and formed with a crank arm at the top and a lever arm at the bottom, said lever arm being connected to the sickle bar by means of a link; independent means 40 for elevating the said connecting brace, said means comprising a chain which is secured to the said connecting brace, passed over a pulley and secured to a lever pivoted to the sliding frame; and means for driving the 45 usual sickle drive shaft, said means being telescopically and pivotally adjustable to meet the relatively raised or lowered position of the said connecting brace.

In testimony whereof I affix my signature.

JULIUS HEINZ.
